E. BUEHRER

HUMIDIFIER

Filed March 23, 1926

UNITED STATES PATENT OFFICE.

EMIL BUEHRER, OF GREEN BAY, WISCONSIN, ASSIGNOR TO THE GEO. KRESS CO., OF GREEN BAY, WISCONSIN, A CORPORATION OF WISCONSIN.

HUMIDIFIER.

Application filed March 23, 1926. Serial No. 96,758.

The invention relates to a device for humidification of air, and more particularly to the class of humidifiers for use in furnaces, latrobes, stoves or the like of the hot air type employed in dwellings and other buildings.

The primary object of the invention is the provision of a device of this character, wherein the hot air chamber or drum of a furnace, latrobe, stove or the like will be supplied with the proper amount of moisture to raise the humidity of artificially heated enclosures simultaneously with the reception of heat therein from said furnace, latrobe, stove or the like.

Another object of the invention is the provision of a device of this character, wherein the water supply thereto is automatically controlled, while the overflow of such supply is entirely eliminated, thus relieving attention thereto and avoiding the necessity of filling and refilling of said device by an attendant.

A further object of the invention is the provision of a device of this character, wherein the construction thereof is novel in form, so as to occupy the least possible space when in use.

A still further object of the invention is the provision of a device of this character, wherein the level of water therein can be maintained constant, and the possibility of overflow is entirely relieved.

A still further object of the invention is the provision of a device of this character, which is comparatively simple in construction, thoroughly reliable and efficient in its purpose, strong, durable, possessing but few parts, automatic in operation, and inexpensive to manufacture and install.

With these and other objects in view the invention consists in the features of construction, combination and arrangement of parts, as will be hereinafter more fully described, illustrated in the accompanying drawing, showing the preferred embodiment of the invention, and pointed out in the claim hereunto appended.

In the accompanying drawing:

Figure 1, is an enlarged plan view of the device constructed in accordance with the invention.

Figure 2, is an enlarged sectional view on

the line 2—2 of Figure 1, showing in detail the water supply control valve.

Figure 3, is an end elevation of the water container or tray.

Figure 4, is a side elevation of a furnace with a portion thereof broken away, showing the device applied.

Figure 5, is a vertical sectional view through the water level indicator.

Similar reference characters indicate corresponding parts throughout the several views in the drawing.

Referring to the drawing, in detail, A, designates generally a furnace of the hot air type, which may be of any desired construction, having at its top the usual hot air chamber or drum B, the furnace being merely illustrated in the drawing for the purposes of disclosing the application of and manner of use of the humidifier hereinafter more fully described.

The humidifier comprises a water container or tray 10, preferably made from sheet metal, and of elongated formation, although the same can be of any required size, shape, and made from any suitable material. This container or tray 10, is positioned within the hot air chamber or drum B, of the furnace A, so as to rest upon the top 11, of the air heater of the furnace, as is shown in Figure 4, of the drawing.

Leading in through the body of the furnace A, is a water supply pipe 12, having a hand operated cut-off valve 13, the elbow 14, of this pipe being extended into the air chamber or drum B, and through the front wall 15, of the container or tray 10, by means of a discharge nozzle 16, having a stepped passage 17, centrally thereof. The smaller bore of the passage 17, at the outlet end of the nozzle 16, is formed with a beveled valve seat 18, for a valve 19, the pin 95 stem 20, thereof being loosely engaged in the smaller bore of the passage 17, for supporting and guiding said valve 19, to and from the seat 18, in the nozzle.

Keyed upon and carried by the free end of the nozzle 16, is a substantially L-shaped bracket 21, the horizontal arm 22, of which has pivoted at 23, therein a rocker link 24, formed with a medial outwardly projecting socketed boss or stud 25, in which is fitted the arm 26, of a ball-float 27, which latter

is adapted to ride upon the surface of the water let into the container or tray 10, and is designed to automatically control the valve 19, for regulating the amount of water 5 to be admitted into the container or tray.

The valve 19, is detachably threaded into a socket piece 28, pivoted at 29, to the link 24, which latter moves said valve 19, to and from its seat 18, in the nozzle 16, when the 10 armed float 27, is active. The level of the water in the container or tray 10, may be varied by adjustment of the valve 19, in the socket piece 28, although it being preferable to have the level of water at the point 15 indicated by the dotted line C, in Figure 3, of the drawing.

Leading from the container or tray 10, exteriorly of the body of the furnace is an emergency overflow pipe 30, having fitted 20 therein a water depth indicator device in the form of a cup or bowl 31 having a depth equal to the depth of the tray 10, and in this cup or bowl is a floating gauge rod 32 of the usual type, the device being of the construction illustrated in Figure 5, of the drawing, and this device will also serve to enable an attendant to note at a glance the water level 25 in the container or tray 10, and thus determine whether or not the valve 19, has failed to function in its closing movement.

In the operation of the invention, assuming that the furnace A, is active or burning, the water is let into the container or tray 10, by opening the valve 13, in the water supply pipe 12, whereupon water will be caused to flow into said container or tray 10, for the filling thereof to the predetermined level therein, namely as indicated by the dotted line C, in Figure 3, of the drawing.

40 When the water reaches the proper level in

the container or tray 10, it is automatically cut off by the valve 19, becoming seated in the valve seat 18, the valve being closed by the operation of the float 27, riding the water surface, and in this manner the valve is 45 automatically actuated.

Should an overflow occur in the container or tray 10, the same will be taken care of by the overflow pipe 30, which may extend to any desirable point or into a sewer. 50

The water within the container or tray 10, will be taken up by the hot air which is transmitted to the various rooms or enclosures in a building in the usual well known manner, thereby insuring moisture in the 55 heated air supplied by such furnace.

What is claimed is:

The combination with the hot air chamber of a heating apparatus, of a humidifier, comprising a water container adapted to be 60 located within said chamber, a water supply pipe, a nozzle extending from the pipe into the container near its top and having a stepped passage, the free end of the nozzle being formed with a valve seat, a bracket 65 on the nozzle, a rocker link pivoted to the bracket and confronting the nozzle, socketed pieces extending in opposite directions from the link, one piece being pivoted to the latter in alignment with the nozzle, a valve adjustably engaged in the pivoted piece to cooperate with the valve seat and having a pin stem projected into the smaller portion of the passage in the nozzle, a float within 70 the container and connected with the other 75 socketed piece, and emergency overflow mechanism leading from the container.

In testimony whereof I affix my signature.

EMIL BUEHRER.
